UNITED STATES PATENT OFFICE.

GUY MORGAN LAIRD, OF HILLSBORO, ILLINOIS.

ATTACHMENT FOR ELECTRIC LAMPS.

1,178,079.

Specification of Letters Patent.

Patented Apr. 4, 1916.

Application filed February 8, 1915. Serial No. 6,828.

To all whom it may concern:

Be it known that I, GUY M. LAIRD, a citizen of the United States, residing at Hillsboro, in the county of Montgomery and State of Illinois, have invented certain new and useful Improvements in Attachments for Electric Lamps, of which the following is a specification, reference being had to the accompanying drawings.

10 My invention relates to attachments whereby an electric lamp may be mounted upon a dry battery, and the primary object of my invention is the provision of a very simple device of this character which may be readily mounted upon any dry battery and connected up therewith, and in which the circuit through the battery is normally broken, but may be completed either intermittently or continuously for any desired 20 length of time.

15 A further object of the invention is to form the attachment of practically one continuous strip of metal bent so as to embrace the battery and clamp upon it to form a handle and form a circuit closer.

25 Other objects will appear in the course of the following description.

My invention is illustrated in the accompanying drawings, wherein—

30 Figure 1 is a top plan view of the attachment, the handle being broken away; Fig. 2 is a side elevation of the attachment applied, the battery being shown in dotted lines and part of the clamping member of the attachment being in section; Fig. 3 is a detail sectional view on the line 3—3 of Fig. 1; Fig. 4 is a detail view showing a portion of the arm and the hook on the circuit closer.

35 Referring to these figures, it will be seen that my attachment is formed of a single strip of metal 2, having uniform width, and in actual practice about twenty-one inches long. One end of the strip 2 is outwardly bent as at 3 and is then bent into a circle so as to surround and clamp upon a dry cell. At a point 4 the material of the strip is outwardly bent and then rebent upon itself to form an outwardly projecting abutment or flange 5 confronting the flange 3 and adapted to be engaged with and drawn toward said flange, to thereby contract the battery clamping ring by means of a bolt 6. After being rebent upon itself as at 5 the bend is continued toward the other end of the strip 55 as at 7 shown in Fig. 3, and is then folded on a line at forty-five degrees to its edge and

extended upward as at 8. The strip is extended upward and then diametrically across the circular band 2 or ring to form a handle 9 which at its forward end is curved downwardly and inwardly as at 10, then extends straight downward as at 11 and is bent outward as at 12 and then extends downward again as at 13. The strip is then rebent upon itself as at 14 and then extended 61 radially inward as at 15 and extended upward as at 16, then outward and upward as at 17, and then is formed with an ear 18 cut so as to provide a hook 19 adapted to engage with the forward curved extremity of the 70 handle 9.

The portion 15 of the strip is perforated to engage with a binding screw 20 on the dry battery 21. Mounted upon the portion 16 of the strip is a U-shaped member 22 which 75 is insulated from the strip by means of the insulating plates 23, as shown clearly in Fig. 1. A conductor 24 is connected to this U-shaped member 22, the other end of the conductor being adapted to be engaged by 80 the binding screw 23 on one pole of the battery. The purpose of bending the strip as at 10 and 12 is to provide a seat for a lamp housing and reflector, designated 25. This strip also carries upon it a metallic socket 26 85 which is threaded for the reception of the usual electric light plug, the outer end of which is designated 27, and is illustrated in Fig. 2. The socket 26 is electrically connected to one pole of the battery by means 90 of the portions 12, 13, 14 and 15 of the strip, while the contact member on the plug is adapted to be electrically connected to the other pole of the battery by forcing the circuit closing portion of the strip outward so 95 as to bring the member 22 in electrical engagement with the extremity of the plug. The portion 15, 16 and 17, in other words, the resilient arm extending upward from the strip which forms the handle at a point beyond the engagement of the strip with the binding screw 20, forms a circuit breaker or 100 a circuit closer. As illustrated, this strip 15, 16 and 17 is formed integral with or in one piece with the strip which forms the handle and therefore the contact member 22, which 105 is also part of the circuit closer, is insulated from this strip. By the term "circuit closer" or "circuit breaker" as used hereafter, I intend to include the strip 16 whether this carries upon it an insulated contact member 22 or whether the strip 16 110

is insulated in any suitable manner from the remainder of the attachment and therefore acts as the contact itself. Normally the resilience of the portions 15, 16 and 17 of the strip forming the circuit closer will hold the contact member 22 away from the plug, but when the circuit closing portion of the strip is forced forward by the action of the thumb on the portion 17 of the strip the circuit will be closed and the lamp will be energized. If the circuit closer 17 of the strip be forced forward and then the hook 19 engaged with the handle, the contact member 22 will be held in electrical engagement with the plug and the lamp will continue to burn until the hook 19 is disengaged from the handle. It will thus be seen that this device may be used either as a flash lamp or as a steadily burning lamp.

20 It will be obvious that this device can be quickly attached to any standard dry battery cell. The lamp may be energized either by the thumb or by a finger of the hand and the light can either be flashed or made continuous. As before stated, the attachment, excepting the lamp, reflector, socket, and the member 22, is made from only one strip of sheet metal. This metal is not riveted and is formed with only four holes punched in it, two for the screw, one for the reflector and base socket, and one for the screw 20.

Having described my invention, what I claim is:

1. A lamp supporting attachment for dry batteries comprising a battery clamping ring adapted to engage around the body of a battery, a handle mounted thereon and arching over the ring, a lamp socket and plug mounted upon the handle adapted to be electrically connected to one pole of the battery, a circuit closing member mounted beneath the handle and operatively connected to the clamping ring, said circuit closing member being adapted to be shifted to a position to close the circuit through the lamp and battery but being resiliently held from such closing position, and means for electrically connecting the circuit closing member to the other pole of the battery.
2. A lamp supporting attachment for dry batteries, comprising a battery clamping ring, a handle mounted thereon and arching over the ring, a lamp socket and plug mounted upon the forward portion of the handle, the socket being adapted to be electrically connected to one pole of the battery, a resilient circuit closing arm mounted beneath the handle and carried upon the clamping ring and adapted to be connected to one pole of the battery, said circuit closing arm being adapted to be shifted into position to close the circuit through the lamp and battery.
3. An attachment of the character described, including battery clamping means,

a handle arching over the battery clamping means, a lamp plug and socket carried upon the handle, the lamp socket being adapted to be electrically engaged with one of the poles of the battery through the handle, and a circuit closing device comprising a resilient arm operatively mounted upon the handle and extending upward rearward of the lamp plug and beneath the handle and adapted to be electrically connected to the other pole of the battery and manually movable into position to close the circuit through the plug and socket.

4. An attachment of the character described, including battery clamping means, a handle arching over the battery clamping means, a lamp plug and socket carried upon the handle, the lamp socket being adapted to be electrically engaged with one of the poles of the battery through the handle, and a circuit closing device comprising a resilient arm operatively mounted upon the handle and extending upward rearward of the lamp plug and beneath the handle and adapted to be electrically connected to the other pole of the battery and manually movable into position to close the circuit through the plug and socket, said arm being formed at its extremity to engage with the handle to hold the arm in its circuit closing position.

5. An attachment of the character described, comprising a strip bent in a circle to engage around a battery, the strip being bent upward, then forward and downward to form a handle arching over the circular portion of the strip, said strip then engaging the circular portion and extending inward and upward to form a resilient circuit closing arm, a lamp socket and plug mounted upon the forward portion of the handle, the socket being adapted to be connected through the handle to one pole of the battery, a contact member mounted upon said circuit closing arm of the strip but insulated therefrom and adapted to be shifted by a movement of said arm into contact with the plug, and an electrical connection extending from the contact member and adapted to be connected to the other pole of the battery.

6. An attachment of the character described, comprising a strip bent to form an open ring adapted to embrace and clamp upon a battery, the strip on one end of the ring being extended upward then forward and then downward and engaged with said ring, the strip then being extended diametrically of the ring to engage one of the binding poles of the battery, then extended upward and forward to form a circuit closing arm and being formed at its extremity with a hook adapted to engage with the adjacent portion of the handle, a lamp socket and plug mounted upon the forward portion of the handle and projecting there-

- through in a position opposite said circuit closing arm, and a contact member carried upon and insulated upon said arm and adapted to be electrically connected with 5 the other pole of the battery, said contact member when the arm is forced outward being electrically engaged with the lamp plug to thereby close the circuit through the lamp.
10. 7. An attachment of the character described, comprising a battery embracing ring, a handle, a circuit closing arm, all formed of a single strip of metal, a circuit closing plug and socket mounted upon the 15 handle portion of the strip, means for connecting the socket to a pole of the battery through the strip, a contact member supported upon but insulated from the circuit closing arm and adapted to be shifted into 20 engagement with the plug, and means for electrically connecting this contact member with the other pole of the battery.
8. An electric lamp and battery supporting attachment comprising a clamping member adapted to engage the body of the battery, a handle arching over the clamping member and attached thereto, a lamp operatively mounted upon the attachment and adapted to be connected in a normally open 25 circuit with the battery poles, and a resilient circuit closing member mounted upon the attachment and disposed entirely within the lines of said handle whereby to protect the circuit closing member from accidental displacement.
9. An electric lamp and battery supporting attachment including a clamping member adapted to engage the body of the battery, a handle arching over the clamping 30 member to provide downwardly extending portions each connected at its lower end to the clamping member, an electric lamp mounted upon and carried by one of the said downwardly extending portions, and 35 including a socket and a plug each adapted to be operatively connected to a corresponding pole of the battery, and a resiliently supported circuit closing member operatively supported on the attachment and extending parallel to the lamp supporting portion of the handle and adapted to be moved into coaction with the lamp to close the circuit therethrough. 50
10. An electric lamp and battery supporting attachment comprising a battery clamping ring adapted to surround and clamp upon the body of the battery, a handle arching over said ring and connected at its depending ends to said ring, an electric lamp socket carried upon the forward portion of the handle, an electric lamp having a plug disposed in said socket, and a circuit breaking device including a resilient strip supported at its lower end upon said attachment and extending upward approximately 60 parallel to the lamp supporting portion of the handle, said circuit breaking device being adapted to be connected to one of the poles of the battery. 55
11. An electric lamp and battery supporting attachment comprising a battery-embracing clamping member adapted to engage the body of the battery, a metallic strip attached to said member at its ends and arching over the member, the forward 65 portion of the metallic strip being inwardly bent, a reflector supported within the bent portion of the strip having a lamp socket, a lamp plug, means for connecting the lamp supporting strip to one pole of the battery, and a circuit closer including a resilient strip operatively connected to said clamping member extending upward approximately parallel to the lamp supporting portion of the handle and adapted to be connected to the other pole of the battery and means for locking the strip in its circuit closing position. 70
- In testimony whereof I hereunto affix my signature in the presence of two witnesses. 75
